(57) **CLAIM**

The ornamental design for a carbon fiber fabric, as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a top plan view of the carbon fiber fabric;
Fig. 1.2 is a bottom plan view of the carbon fiber fabric;
Fig. 1.3 is a top plan view of the carbon fiber fabric with the carbon fiber fabric under incident light at 45 degrees;
Fig. 1.4 is a top perspective view of the carbon fiber fabric with the carbon fiber fabric inclined at 45 degrees under incident light at 45 degrees;
Fig. 1.5 is a top perspective view of the carbon fiber fabric with the carbon fiber fabric inclined at 20 degrees under incident light at 45 degrees;
Fig. 1.6 is a top perspective view of the carbon fiber fabric with the carbon fiber fabric inclined at 45 degrees under ordinary light;
Fig. 1.7 is a top perspective view of the carbon fiber fabric with the carbon fiber fabric inclined at 20 degrees under ordinary light;

(Continued)

Fig. 1.8 is an expanded top plan view of a portion of the carbon fiber fabric of Fig. 1.1 that has been enlarged; Fig. 1.9 is an expanded bottom plan view of a portion of the carbon fiber fabric of Fig. 1.2 that has been enlarged; Fig. 2.1 is another top plan view of the carbon fiber fabric shown with color; Fig. 2.2 is another bottom plan view of the carbon fiber fabric shown with color; Fig. 2.3 is another top plan view of the carbon fiber fabric shown with color and with the carbon fiber fabric under incident light at 45 degrees; Fig. 2.4 is another top perspective view of the carbon fiber fabric shown with color and with the carbon fiber fabric inclined at 45 degrees under incident light at 45 degrees; Fig. 2.5 is another top perspective view of the carbon fiber fabric shown with color and with the carbon fiber fabric inclined at 20 degrees under incident light at 45 degrees; Fig. 2.6 is another top perspective view of the carbon fiber fabric shown with color and with the carbon fiber fabric inclined at 45 degrees under ordinary light; Fig. 2.7 is another top perspective view of the carbon fiber fabric shown with color and with the carbon fiber fabric inclined at 20 degrees under ordinary light; Fig. 2.8 is an expanded top plan view of a portion of the carbon fiber fabric of Fig. 2.1 that has been enlarged shown with color; and Fig. 2.9 is an expanded bottom plan view of a portion of the carbon fiber fabric of Fig. 2.2 that has been enlarged shown with color.
